UNITED STATES PATENT OFFICE.

WILLIAM JEFFERSON SANDERS, OF GILMER, TEXAS.

HEARTH GUARD OR SHIELD.

SPECIFICATION forming part of Letters Patent No. 315,345, dated April 7, 1885.

Application filed May 22, 1884. (No model.)

To all whom it may concern:

Be it known that I, WILLIAM J. SANDERS, a citizen of the United States, and a resident of Gilmer, in the county of Upshur and State 5 of Texas, have invented certain new and useful Improvements in Hearth Guards or Shields; and I do hereby declare that the following is a full, clear, and exact description of the invention, which will enable others 10 skilled in the art to which it appertains to make and use the same, reference being had to the accompanying drawings, which form a part of this specification, and in which—

Figure 1 is a perspective view of my improved hearth-guard, illustrating its application to a fire-place. Fig. 2 is a similar view of the guard or shield removed from the fire-place; and Fig. 3 is a sectional view through the plane indicated by the broken line xx .

20 Similar letters of reference indicate corresponding parts in all the figures.

My invention has relation to devices for protecting the hearth and jambs of fire-places; and it consists in the detailed construction of 25 the sheet-metal guard or shield, which will be hereinafter more fully described and claimed.

In the accompanying drawings, A denotes the mantel, B the jambs or sides, and C the floor, of a fire-place which is fitted with my 30 improved guard. The latter is made of any desired sheet metal, of suitable weight or thickness, in a single piece cut from a rectangular plate with straight sides, the said rectangular plate or blank being cut to form an 35 opening, D, opening up into a larger or wider opening, E. After this is done the plate is bent at the point where the openings D and E open up into each other, at right angles, forming the vertical part F and horizontal part G, the vertical or upright part having shoulders 40 or projections H on opposite sides, formed by

the increased width of the aperture E as compared with D. The bent plate F G is provided with a double series of nail-holes, I and J, along its outer and inner edges, for its permanent attachment, by screws or nails, to the sides, top, and floor of the fire-place. The object of the shoulders or projecting parts H is to permit that part of the shield to be properly fitted to the grate and jambs, which 45 can readily be done, so as to fit grates of various sizes by bending the said parts H H more or less, and by cutting notches K K in the projecting edges H H, of such shape and size that the edges will not interfere with the sides of 50 the grate when bent around the corners of the jamb, which obviously could not be done if the inner sides of the opening D were flush or even with the sides of the larger horizontal opening, E.

Having thus described my invention, I claim and desire to secure by Letters Patent of the United States—

The herein-described hearth guard or shield, the same consisting of a rectangular plate of 65 sheet metal cut out to form the inside openings, D and E, of different size, and bent at right angles at the point where the smaller opening, D, in the vertical or upright part F opens into the larger opening, E, in the horizontal part G, thereby forming projections or inside shoulders, H H, having notches K K, adapted to be bent to fit the sides of the grate, substantially as and for the purpose set forth.

In testimony that I claim the foregoing as 70 my own I have hereunto affixed my signature in presence of two witnesses.

WILLIAM JEFFERSON SANDERS.
